BERTHA F. WERNER AND ONE-THIRD TO AUBREY L. ASHBY, BOTH OF PITTS-
BURGH, PENNSYLVANIA.

VALVE.

Application filed May 14, 1924. Serial No. 713,219.

To all whom it may concern:

Be it known that I, JAMES G. WERNER, a citizen of the United States, and a resident of Pittsburgh, in the county of Allegheny and State of Pennsylvania, have invented a new and useful Improvement in Valves, of which the following is a specification.

My invention relates to valve devices and particularly to check valves to be used in connection with fluid-measuring pumps.

One object of my invention is to provide a check valve that shall effectively prevent the leakage of the fluid after it has been drawn through the valve.

Another object of my invention is to provide a valve, of the above-indicated character, that shall have means for effectively positioning the same away from the bottom of the fluid receptacle.

Another object of my invention is to provide a valve that shall have strainers so located therein that sediment from the bottom of the fluid receptacle in which it is disposed will not be drawn through the valve.

Another object of my invention is to provide a valve device that shall be effective irrespective of the inclination of the same when installed.

Another object of my invention is to provide a valve device, of the above-indicated character, that shall have two portions secured together by bolts to permit ease in disassembling the device.

A further object of my invention is to provide a valve device, of the above-indicated character, that shall be self seating, positively actuated, yet simple in construction and effective in its operation.

In practicing my invention, I provide a two part casing, the two parts of which are secured together by bolts. The lower part of the casing is provided with a spacing foot and wire mesh screens in the sides thereof. A valve member having an annular tin insert co-operates with a valve seat in the lower part of the casing. A spring is disposed between a guide in the upper part of the casing and the valve for positively seating the same, and a guide is provided in the lower part of the casing to prevent the valve from turning.

With the above arrangement, the valve

will always seat itself irrespective of the inclination of the casing and proper screening of the fluid being measured, such as gaso- 55 line, will be obtained. Also the device may be easily disassembled for inspection and adjustment.

The single figure of the accompanying drawing is a view, partially in elevation, 60 partially in section and partially diagrammatic, of a check valve device embodying my invention applied to a gasoline pump.

A gasoline pump and measuring device 1 is connected through a pipe 2 to a gasoline 65 tank or receptacle 3 which is usually located below the surface of the ground. A check valve 4 is connected to the lower end of the pipe 2 to prevent the leakage back into the tank 3 of gasoline which has been drawn 70 into the sentry or measuring device 1.

The check valve 4 comprises, in general, a two-part casing, the upper part 5, of which is screw threaded to the pipe 2 and the lower part 6 of which is provided with 75 a bottom plate 7 that is screw threaded to the part 6 and provided with a spacing foot 8 that rests against the bottom of the receptacle 3. The bottom plate 7 is also provided with a projection 9 having a slot 10 80 therein for purposes hereinafter set forth. Windows 11 are provided in the lower part 6 of the casing and wire mesh screens 12 are disposed in the windows to strain the gasoline. 85

The two parts of the casing are provided with flanges 13 and 14 that have corresponding bolt holes therein to receive bolts 15 to secure the two parts of the casing together.

The lower part of the casing has an internal flange 16 which constitutes a valve seat. A valve disk or member 17 is disposed in the casing and it has two projections or guide rods 18 and 19 thereon. The guide rod 19 is disposed in the projection 9 95 and has a pin 20 therein that is disposed in the slot 10 for the purpose of preventing the disk 17 from turning. The upper projection or rod 18 of the valve is guided by a guiding member 21 that forms a part of the 100 upper part 5 of the casing. A spring 22 surrounds the rod 18 and is disposed between the guide member 21 and the disk 17 for the purpose of positively seating the disk ir-

respective of the inclination of the casing. The spring is just strong enough to permit the suction of the pump 1 to unseat the valve, but when the suction is removed the 5 spring immediately reseats the valve.

- The disk 17 is usually made of brass or other relatively hard material as is also the valve seat 16. The disk 17 has an annular groove 23 therein in which is deposited a 10 tin or other relatively soft metal insert 24. The tin insert 24 bears upon the inclined face of the valve seat and by reason of its relative softness it will insure an effective seating, and of course, no leakage will occur. 15 It has been found that with this type of valve seat it is necessary to prevent the two parts of the valve from turning relatively for such movement would cut annular grooves in the tin insert 24. This is accomplished by the pin 20 and the slot 10 in the guide 9. It has been further found that a 20 valve of this type will continue to readjust its seat until all of the tin insert has been worn away. 25 In order to inspect the device, it is only necessary to remove the bolts 15 and separate the two parts of the housing. The separation of the two parts of the housing releases the disk 17 and it may be readily 30 withdrawn without further manipulation.

It will be noted that the spacing foot 8 is provided to raise the windows 11 above such silt that may be in the bottom of the receptacle 3 and the windows 11 are placed 35 in the side of the casing instead of in the bottom for a similar purpose.

In order to prevent scale and dirt from the pipe 2 from entering the chamber of the valve 4, a mesh screen 25 is provided. 40 The screen 25 has a ring 26 at its outer edge that is provided with screw threads to engage the threads in the upper part 5 of the valve 4. The screen 25 is screwed into its position as shown before the valve 4 45 is screwed onto the lower end of the pipe 2, and may be removed at any time by removing the valve 4 from the pipe 2 and unscrewing the screen from its position. The conical form of the screen as shown per- 50 mits scale and dirt that falls back from the pipe 2 to be collected in an annular groove 27 near the periphery of the screen 25, thereby leaving the central portion of the screen clear to permit free passage of fluid from the tank 3 upwardly there- 55 through.

While I have found that the valve herein illustrated gives excellent results in that it prevents the gasoline pump from delivering less than is indicated because it prevents the gasoline from leaking back into the receptacle, it is conceivable that various modifications may be made without departing from 60

the spirit and scope of my invention, as set forth in the appended claims. 65

I claim as my invention:

1. A check valve for fluid pumps comprising a two-part hollow casing, means for bolting the parts together, a bottom plate for the lower part of the casing screw 70 threaded thereto and having a spacing foot extending outwardly therefrom, wire mesh screens in the sides of the lower part of the casing, a spring-restrained valve member seated above the screens in the lower 75 part of the casing, and a guide for the valve member disposed in the upper part of the casing.

2. A check valve for fluid pumps comprising a two-part hollow casing, means for bolting the parts together, a bottom plate for the lower part of the casing screw 80 threaded thereto and having a spacing foot extending outwardly therefrom, wire mesh screens in the sides of the lower part of the casing, a valve member seated above the screens in the lower part of the casing, a 85 guide member for the valve member disposed in the upper part of the casing, a spring disposed between the guide member 90 and the valve member, and means mounted on the bottom plate to preclude the valve member from turning.

3. A check valve for fluid pumps comprising a casing having a valve seat therein, 95 a spring pressed valve member having a soft metal insert for engaging the valve seat, and means to prevent relative turning movement between the valve member and the seat.

4. A check valve comprising a co-operating valve seat and a movable member constructed of relatively hard material, a tin insert in one of the co-operating members, and means for preventing the members from turning relatively to each other. 100

5. A check valve for a fluid pump comprising a casing, a foot on the lower part of the casing for spacing the valve from the bottom of the fluid receptacle in which it is disposed, and a spring-actuated, self-seating, non-rotatable valve in the casing. 110

6. A check valve comprising a casing having a spacing foot at the bottom thereof, wire screens in the sides only thereof, and a valve therein that will properly seat irrespective of the inclination of the casing. 115

7. A valve device of the character described comprising a conical mesh screen in the upper portion thereof to preclude the entrance of undesirable matter into the valve 120 chamber from the apparatus thereabove.

In testimony whereof, I have hereunto subscribed my name this 26th day of April 1924.

JAMES G. WERNER.
